UNITED STATES PATENT OFFICE

2,625,995

CAM-ACTING TENSION DEVICE FOR
FRAMELESS WINDOW SCREENS

David Jordan Rust and Jack H. Jensen, San Leandro, Calif., assignors to Ry-Lock Company, Ltd., San Leandro, Calif., a corporation of California

Application April 30, 1951, Serial No. 223,764

2 Claims. (Cl. 160—328)

1

This invention pertains generally to improvements in frameless window screens.

In particular the invention relates to, and it is an object to provide, a novel device for tensioning a frameless window screen.

Such tensioning device includes an initially upstanding cam lever pivotally mounted in connection with the window frame for downward swinging motion in a lateral direction; the cam of such lever being at its lower end portion and engaging in a channel fixed on the bottom cross bar of the screen, and said cam acting to forcefully lower the bottom cross bar and to thus tension the screen upon the cam lever being so swung.

As the cam has a rotary motion when the cam lever is swung between an upstanding released position and a lowered screen tensioning position, with such motion in a laterally outward direction at the lower, channel engaging edge, there is a tendency for said cam to undesirably shift the channel and attached bottom cross bar in a corresponding lateral direction with possible improper positioning of the screen under tension in the window opening.

It is therefore an important object of the invention to provide a novel cam and channel assembly which is operative to impart the desired tension to the screen, but also acts in a manner to prevent outward lateral displacement of the channel and bottom cross bar by rotary motion of the channel engaging cam.

Another object of the invention is to provide a tensioning device, as in the preceding paragraph, wherein the tendency of the channel and bottom cross bar to displace laterally in an outward direction is counteracted by inclining the channel upwardly in the opposite direction.

It is also an object of the invention to provide a cam-acting tension device for frameless window screens which is designed for ease and economy of manufacture.

Still another object of the invention is to provide a practical and reliable tensioning device for frameless window screens, and one which will be exceedingly effective for the purpose for which it is designed.

These objects are accomplished by means of such structure and relative arrangement of parts as will fully appear by a perusal of the following specification and claims.

In the drawings:

Fig. 1 is a fragmentary rear elevation of a frameless window screen showing a pair of the tensioning devices as used in connection there-

2

with; the cam lever of the right-hand device being in its upstanding released position, while the cam lever of the left-hand device is in its lowered screen tensioning position.

5 Fig. 2 is a cross section on line 2—2 of Fig. 1, but with the cam lever raised.

Fig. 3 is a cross section on line 3—3 of Fig. 1.

Referring now more particularly to the characters of reference on the drawings, the frameless window screen is here shown as disposed in a window frame, indicated generally at 1, which frame includes, at opposite sides 2, the usual vertical blind stops 3. The sill is indicated at 4.

The frameless window screen is of the type which includes a section of wire cloth 5 fitted with a bottom cross bar 6 and a top cross bar (not shown); the latter being secured to the header of the window frame 1 by suitable means.

10 The bottom cross bar 6 includes a vertically adjustable U-shaped bottom strip 7 whose purpose is to provide a full closure between the bottom cross bar 6 and the top of the sill 4.

15 The section of wire cloth 5 is normally maintained under tension or taut by means of tensioning devices, indicated generally at 8; there being a pair of said devices, each working between one of the blind stops 3 and the corresponding end portion of the bottom cross bar 6.

20 As the tensioning devices 8 are of identical construction, except for being right and left hand, a description of one will suffice for both.

25 Each tensioning device 8 comprises an elongated mounting strip 9 secured in fixed relation to the back side of the bottom cross bar 6 above the bottom strip 7; such mounting strip 9 including, in integral relation, an upwardly opening catch channel 10 which is disposed closely adjacent, but terminates short of, the corresponding end of the bottom cross bar 6, whereby said catch channel does not engage the related blind stop 3.

30 The catch channel 10 is disposed at an upward incline from its laterally outermost end; the purpose of this inclination being hereinafter described.

35 An integral deflector tongue 11 extends at an outward and downward incline from the rear upper edge of the catch channel 10, while a finger pull 12 projects rearwardly and upwardly from the mounting strip 9 laterally inwardly of said catch channel 10.

40 A bracket unit, indicated generally at 13, and which is described in detail in my copending application, Serial No. 223,763, filed April 30, 1951, 45 is secured to the adjacent side of the correspond-

ing blind stop 3 directly beyond but mainly above the catch channel 10; said bracket unit including a vertically adjustable attachment plate 14 affixed to the blind stop 3 by a headed screw 15 which works through a vertical slot 16 in said plate 14.

An integral bracket plate 17 projects at a right angle to the attachment plate 14 in a horizontal, laterally inward direction, and serves as the mount for a flat cam lever, indicated at 18.

At its lower end portion the cam lever 18 is pivoted, as at 19, in face to face engagement with the bracket plate 17, for swinging between an upstanding released position, as at the right in Fig. 1, and a lowered screen tensioning position as at the left in such figure. At the end portion opposite the pivot 19 the cam lever 18 includes a finger tab 20 to facilitate manipulation of said lever.

The pivoted lower end portion of the lever 18 forms an eccentric rotary cam, indicated at 21; this being accomplished by making the distance between the pivot 19 and the rounded or arcuate initially lower edge 22 of the lever less than the distance between such pivot and the initially laterally inner straight edge 23 of the lever 18.

Thus, when the lever 18 is swung downward from its upstanding position to a substantially horizontal position, the cam 21, working in the catch channel 10, urges the latter—together with the bottom cross bar 6—downwardly, forcefully effectively tensioning the screen. In its lowered, screen tensioning position the lever 18 passes dead-center—with respect to the cam shape—and is thus in effect releasably latched.

Upon the cam lever 18 being swung from its upstanding released position to its lowered screen tensioning position, the cam 21 turns in a laterally outward direction at the bottom; i. e. below the pivot 19. The result is a tendency of the part-turning or rotating cam to shift the catch channel 10 and the bottom cross bar 6 likewise in a laterally outward direction; there normally being some end play between the bottom cross bar 6 and opposite sides of the window frame 1. It is undesirable that such displacement of the bottom cross bar 6 occur, as this misalignes the screen in the window frame 1 and prevents proper tensioning thereon by the transversely spaced tensioning devices 8.

It is therefore necessary that such tendency of the bottom cross bar 6 to displace in a laterally outward direction be counteracted, and this is accomplished by inclining each catch channel 10 in the manner heretofore described. With the catch channel 10 inclined upwardly in a laterally inward direction, an opposed force is produced when the cam 21 is part-rotated, which force counteracts the tendency of the cross bar 6 to displace in said laterally outward direction. The expedient employed for the purpose is simple, but nevertheless is most effective to accomplish the desired end; to-wit, the maintenance of the frameless window screen in proper alinement in the window frame 1 when the tensioning devices 8 are manipulated to their screen tensioning positions.

The finger pull 12 is used to initially draw the

bottom cross bar 6 against the blind stops 3, whence the lower or cam end of the lever 18 engages the deflector tongue 11 and easily snap-engage in catch channel 10.

From the foregoing description it will be readily seen that there has been produced such a device as substantially fulfills the objects of the invention, as set forth herein.

While this specification sets forth in detail the present and preferred construction of the device, still in practice such deviations therefrom may be resorted to as do not form a departure from the spirit of the invention, as defined by the appended claims.

Having thus described the invention, the following is claimed as new and useful, and upon which Letters Patent are desired:

1. In a tensioning device for a frameless window screen having a bottom cross bar extending between opposite sides of a window frame; a cam lever pivoted in connection with the window frame at one side thereof and adjacent the bottom cross bar, the cam lever being swingable downwardly from an upstanding released position in a direction parallel to the screen and to a lowered screen tensioning position, an upwardly facing element fixed on the bottom cross bar below the lever; the lower end portion of the lever being a rotary cam abutting said element, said cam turning at the bottom edge in a laterally outward direction and simultaneously thrusting downwardly upon swinging of the lever, and said element being inclined upwardly in an opposite direction whereby to counteract the tendency of the turning cam to displace said element and the cross bar in said laterally outward direction.

2. In a tensioning device for a frameless window screen having a bottom cross bar extending between opposite sides of a window frame; a cam lever pivoted in connection with the window frame at one side thereof and adjacent the bottom cross bar, the cam lever being swingable downwardly from an upstanding released position to a lowered screen tensioning position in a direction parallel to the screen, and an upwardly opening longitudinal channel fixed on the bottom cross bar below the lever, the lower end portion of the lever being a rotary cam engaged in the channel, said cam turning at the bottom edge in a laterally outward direction and simultaneously thrusting downwardly upon swinging of the lever, and said channel being inclined upwardly in an opposite direction whereby to counteract the tendency of the turning cam to displace the said channel and the cross bar in said laterally outward direction.
